UNITED STATES PATENT OFFICE.

GEORGE L. WALKER AND IVORY W. HARLOW, OF PLYMOUTH, MASSACHUSETTS, ASSIGNORS TO THE PLYMOUTH FOUNDRY COMPANY, OF SAME PLACE.

GRATE FOR STOVES OR FURNACES.

SPECIFICATION forming part of Letters Patent No. 460,710, dated October 6, 1891.

Application filed April 9, 1891. Serial No. 388,223. (No model.)

To all whom it may concern:

Be it known that we, GEORGE L. WALKER and IVORY W. HARLOW, citizens of the United States, both residing at Plymouth, in the county of Plymouth and State of Massachusetts, have invented a new and useful Improvement in Grates for Stoves or Ranges, of which the following is a full, clear, and exact description, reference being had to the accompanying drawings, forming a part of this specification, in explaining its nature.

The invention relates to a grate for stoves or ranges, comprising a flat plate having an oval or other shaped opening and adapted to be supported by its edges in any desirable way in the stove and to support the fire-brick or lining of the stove, which plate has downwardly-extending lugs, one at its rear supporting a pivot and one at each of the front corners, forming a rest. The pivot and rests carry and support a movable open-work plate, which forms the principal part of the grate bottom, and which is adapted to be oscillated upon the pivot, the grate-bottom being suspended from the first-named plate. In the bottom plate there is a large central hole, which is closed by a slide-plate having a long slotted arm, by means of which the slide is moved from the hole and the grate-bottom oscillated. The entire construction comprises only three parts—the slide-plate and arm, the grate-bottom, and the plate from which the grate-bottom is suspended.

In the drawings, Figure 1 is a view in plan of the flat plate above referred to, a portion of the plate being broken out. Fig. 2 is a view in end elevation thereof, taken through the rear. Fig. 3 is a view in plan of the parts represented in Fig. 1 reversed. Fig. 4 is a view in plan of the grate-bottom. Fig. 5 is a view in front elevation thereof. Fig. 6 is a view in plan of the grate-bottom reversed. Fig. 7 is a view in plan, reduced in size, of the slide-plate. Fig. 8 is a view in plan of the assembled grate. Fig. 9 is also a view in plan of the assembled grate, the grate-bottom and slide occupying a different position from that represented in Fig. 8.

Referring to the drawings, A is the plate, from which the grate-bottom B is suspended.

The plate A is supported in the stove or range in any desired manner, and it has the large oval or other shaped opening a and the narrow upwardly-extending rim a' about it. The surface a^2 of the plate outside the rim serves 55 as a rest for the fire-brick or lining to the combustion-chamber. From the under side of the plate A there project downward three principal lugs or supports: first, the rear lug a^3 , this has the flat inwardly-extending surface 60 a^4 , from which rises a pivot a^5 ; second, the front corner-lugs a^6a^7 . Each of these projects downward from a front corner of the plate A and has a flat resting-surface a^8 . The plate A also has extending down about the opening a the 65 short fingers a^9 . (See Fig. 2.)

The grate-bottom B has an exterior ring b , in the edge of which is arranged recesses b' and the interior ring b^2 , which is lower than the exterior ring and connected with it by 70 bars b^3 , which form open spaces b^4 . The bottom B also has at its rear the angular pocket b^5 , of a size to receive the horizontal portion of the lug a^3 , and a pivot-hole b^6 , into which the pivot a^5 extends. It also has at each forward corner the rails or supports b^7 , which extend laterally from the ring b to rest upon the upper surfaces of the horizontal portions a^8 of the lugs a^6a^7 , the rails being of a sufficient length to permit of the travel or oscillating 75 movement of the grate-bottom upon said surfaces. The grate-bottom also has at one end the downwardly-extending pin b^8 . The end b^9 of the central ring b^2 of the grate-bottom is cut away to allow a slide-plate to be moved 80 over the holding-lugs b^{10} . This slide-plate C, when in position upon the lugs, closes the hole b^{11} in the grate-bottom. The plate C is shaped as represented in Fig. 7. It has the spaces c and the long arm c' , in which is a 85 long recess or slot c^2 . This arm extends to a door or opening in the stove and provides means whereby the slide-plate may be moved to open the hole b^{11} in the grate-bottom. It also serves as a means of oscillating the grate, 90 as the pin b^8 of the grate-bottom passes into and through the long slot or recess c^2 , so that by oscillating or moving the handle back and forth the grate-bottom and slide are caused 95 to be oscillated or shaken.

By hanging the grate-bottom as specified it will be easily oscillated. By providing it with the large hole in the bottom means are afforded for the removal of dead ashes, clinkers, &c.

We do not wish to be understood as broadly covering these features, however, our invention comprising rather the broad and specific means of embodying these features in a cheap and strong construction.

Having thus fully described our invention, we claim and desire to secure by Letters Patent of the United States—

1. The improved grate comprising the plate 15 A, having the central opening a and the downwardly-extending pivot-lug a^3 , and the downwardly-extending rest-lugs a^6 a^7 , cast with the

plate A, and the grate-bottom B, having a pivot-hole to receive the pivot a^5 and the supports b^7 to rest upon the surface a^8 of the 20 lugs a^6 a^7 , as and for the purposes described.

2. The combination, in a grate, of the plate A, having the central opening a , the downwardly-extending pivot-lug a^3 , and the lugs a^6 a^7 , and a grate-bottom B, supported by said 25 pivot and lugs and having the opening b^{11} and pin b^8 , with the slide C, having the arm c' , provided with the slot c^2 , into which the pin b^8 extends, as and for the purposes described.

GEORGE L. WALKER.
IVORY W. HARLOW.

In presence of—
B. A. HATHAWAY,
ELMER F. SHAW.
